UNITED STATES PATENT OFFICE.

DOMINICK D. BARTOLOMEO, OF TROY, NEW YORK.

LICENSE-PLATE FOR AUTOMOBILES.

1,250,543.

Specification of Letters Patent. Patented Dec. 18, 1917.

Application filed February 2, 1917. Serial No. 146,245.

To all whom it may concern:

Be it known that I, DOMINICK D. BARTOLOMEO, a citizen of the United States, residing at Troy, county of Rensselaer, and State 5 of New York, have invented certain new and useful Improvements in License-Plates for Automobiles, of which the following is a specification.

Reference may be had to the accompanying drawings, and the reference characters marked thereon, which form a part of this specification. Similar characters refer to similar parts in the several figures therein.

The principal object of the invention is 15 to employ the license-plate of an automobile as a protection against the theft of the automobile.

Other objects will appear in connection with the following description:

20 Figure 1 of the drawings is a view in perspective of a device embodying my invention.

Fig. 2 is a view in perspective of the same with the parts in an intermediate position in 25 the operation of reversing the identification-plate upon the supporting-plate.

Fig. 3 is a view similar to Fig. 1 with the identification-plate locked in reversed position with relation to the supporting-plate.

30 Referring to the drawing wherein the invention is shown in preferred form, 1 is a supporting-plate, provided with slots, 2, whereby it can be readily attached to an automobile or similar vehicle in the same manner that ordinary license plates are now attached.

This supporting-plate, 1, is preferably also provided with an elongated aperture, 3, adapted to transmit light therethrough from 40 a lamp or lantern placed in rear of said plate, (not shown.)

An identification-plate, 4, is reversibly mounted upon the supporting-plate, 1, by means of a pair of links, 5, connecting the 45 upper end-portions of the supporting-plate, 1, with the respective middle end-portions of the identification-plate, 4, the opposite ends of the links, 5, being pivotally connected to the respective plates.

50 This arrangement permits the identification-plate, 4, to lie either substantially flat upon the supporting-plate, 1, as shown in Figs. 1 or 3, or to be swung away from the supporting-plate, 1, to a position as shown 55 in Fig. 2, in which the identification-plate can be rotated upon the links, 5, to bring it

into reversed relation to the supporting-plate, 1.

The supporting-plate, 1, and identification-plate, 4, are adapted to be locked together in either normal relation or reversed relation by key-controlled mechanism, as a padlock, 6, the hasp of which extends through registering apertures, 7, in the supporting-plate, and 8 in the identification- 65 plate.

The identification-plate bears a display of identification characters, 9, which are preferably the license number of the automobile as required by law, and these characters, 9, 70 are displayed in normal order on the obverse side only of the identification-plate, as in Fig. 1.

These identification characters, 9, are preferably outlined by openings formed 75 through the identification-plate, 4, as shown, whereby they are readable by light transmitted through the aperture, 3, in the supporting-plate and the apertures in said characters, from a lamp or lantern, not shown, 80 mounted in rear of the supporting-plate, 1.

As shown in Fig. 1, when the identification-plate is locked in normal relation to the supporting-plate, 1, the display of characters, 9, is substantially the same as the display on an ordinary license plate. 85

When it is found necessary to leave the automobile unguarded for a time, the padlock, 6, is opened and the identification-plate, 4, is reversed with reference to the 90 supporting-plate, 1, to the position shown in Fig. 3, in which position it is locked by the padlock, 6.

In this reversed position on the identification-plate the characters, 9, are either not 95 displayed at all on the reverse side of the plate if not outlined by openings; or, if outlined by openings as preferred, said characters are inverted and reversed, so that attention will be readily called to either the absence of the characters or the inversion and reversal of the characters, should the automobile be driven with the identification-plate in this reversed position. 100

A person contemplating the theft of an 105 automobile would probably be deterred by the reversed and locked license plate; or if he should persist, the irregularity of his conduct would at once be revealed by either the absence of the normal license number or the 110 inverted and reversed position of the characters comprising said number.

The reverse side of the identification-plate may bear a minor display, 10, of the same characters which constitute the major-display, 9, which will enable the license number of the automobile to be readily determined, although not legally displayed, when the identification-plate is in reversed relation to the supporting-plate, 1.

What I claim as new and desire to secure by Letters Patent is—

- 10 1. In a device of the class described and in combination, a supporting-plate provided with means whereby it can be attached to a vehicle; an identification-plate reversibly mounted on said supporting-plate, said identification-plate bearing a major-display of identification characters, displayed in normal order on its obverse side only, and also bearing a minor display of the same characters displayed informally on its opposite side; and key-controlled means for locking the identification-plate in reversed position upon the supporting-plate.
- 15 2. In a device of the class described and in combination, a supporting-plate provided with means whereby it can be attached to a vehicle; an identification-plate bearing a dis-

play of identification characters displayed in normal order on its obverse side only; a pair of links connecting the upper end-portion of the supporting-plate with the respective middle end-portions of the identification-plate whereby the identification-plate is reversibly mounted on the supporting-plate; and key-controlled means for locking the identification-plate in reversed relation to the supporting-plate.

- 30 3. In a device of the class described and in combination, a supporting-plate apertured to transmit light, and provided with means whereby it can be attached to a vehicle; an identification-plate reversibly mounted upon said supporting-plate, said identification-plate bearing a display of identification characters outlined by openings therethrough, said characters being displayed in normal order on the obverse side only thereof; and key-controlled means for locking the identification-plate in reversed relation to the supporting-plate.
- 35 40 45 50

In testimony whereof, I have hereunto set my hand this 22nd day of January, 1917.

DOMINICK D. BARTOLOMEO.
